(57) **CLAIM**

The ornamental design for a tool, as shown and described.

DESCRIPTION

FIG. 1 is a front, top, right hand side perspective view of a tool embodying the principles of my our design;

FIG. 2 is a front, left hand side perspective view thereof;

FIG. 3 is a side view thereof as seen from the left hand side of FIG. 1;

FIG. 4 is a side view thereof as seen from the right hand side of FIG. 1;

FIG. 5 is top view thereof;

FIG. 6 is a front view thereof;

FIG. 7 is a rear view thereof; and,

FIG. 8 is a bottom view thereof.

The tool being shown with a control panel in FIGS. 1, 2, 3 and 5 in phantom lines and forming no part of the claimed design; and FIG. 1 showing the tool with the battery removed for clarity of illustration only.

UNITED STATES PATENT AND TRADEMARK OFFICE
CERTIFICATE OF CORRECTION

PATENT NO. : D651,498 S
APPLICATION NO. : 29/346435
DATED : January 3, 2012
INVENTOR(S) : Mirco Neeser, Flavio Finzo and Roland Widmer

Page 1 of 1

It is certified that error appears in the above-identified patent and that said Letters Patent is hereby corrected as shown below:

Title Page, Description, Col. 2, line 2;
The phrase "embodying the principles of my our design" should read, "embodying the principles of
our design".

Signed and Sealed this
Nineteenth Day of June, 2012

David J. Kappos
Director of the United States Patent and Trademark Office
